UNITED STATES PATENT OFFICE.

LEWIS J. BAZZONI, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

BUTTONING MACHINE.

Application filed September 8, 1924, Serial No. 736,584, and in France June 7, 1924.

This invention relates to buttoning machines. The invention is illustrated as embodied in a step-by-step buttoning machine designed for use upon finished shoes.

5 Buttoning machines are commonly provided with button-supporting devices in which the buttons to be operated on are inserted before the machines are started. In step-by-step machines, the buttons have 10 heretofore been supported in raceways disposed in an approximately horizontal plane so that the shanks of the buttons have been positioned substantially vertically. While such an arrangement is highly advanta- 15 geous for use in buttoning shoe uppers before lasting and, indeed, for various purposes, the buttoning of finished shoes presents a special problem because of characteristics of finished shoes as distinguished from 20 such articles as shoe uppers, gaiters, and the like. The buttons and buttonholes on a finished shoe extend along a curved path which is angularly related to the bottom of the shoe and hence to the top of the toe of the shoe. 25 The common practice in the packing rooms of shoe factories is to button all the buttons of finished shoes prior to putting them in their cartons, and the line of the buttons near the top of a shoe is at a very marked 30 angle with the toe of the shoe. As a consequence, when the buttons of a finished shoe are inserted in a horizontal button raceway, the weight of the shoe as a whole, and in particular of the heel of the shoe, tends to 35 twist the shoe out of its natural shape and to raise the top of the toe of the shoe toward the under side of the raceway. Under these 40 conditions, the toe will, therefore, be brought past the operating instrumentalities of the machine either at the beginning or at the completion of the buttoning operations accord- 45 ingly as it is a right or left shoe. This makes it difficult to prevent injury to the shoe and in particular to the top of the toe, and the difficulty is all the more pronounced 50 because of the fact that slight scars, which might be disregarded at other stages of the work, are a serious drawback when the shoe has reached the packing room because here the shoe is substantially ready to be inserted

in its carton and sent on to the customer and must present its most favorable appearance.

In view of the foregoing, an object of the present invention is to provide an improved 55 buttoning machine in which finished shoes may be buttoned without danger of injury to the shoe. In the illustrated embodiment of the machine, this and other objects are attained by disposing the button raceway in a substantially vertical plane, the button shanks being thereby positioned horizontally so that the natural weight of the shoe will hold the shoe in a position more or less parallel to the face of the raceway and the 60 machine and will keep the toe of the shoe in such position that there is no tendency for it to contact with the raceway or the 65 operating instrumentalities.

In accordance with a further feature of 70 the invention, the raceway plate is disposed upon the front of the machine, and substantially all the operating instrumentalities of the machine, including the cam shaft for operating the operating instrumentalities, 75 are arranged behind the raceway plate. This further facilitates the desired protection of the shoe since the finished shoe will be disposed on one side of said raceway plate while the operating instrumentalities of the 80 machine are on the other side of and concealed by the plate. In the illustrated em- 85 bodiment the button feeding finger is the only moving part disposed in front of the raceway.

Another feature of the invention resides in the arrangement of the various mech- 90 anisms of the machine, such as the driving, controlling and operating mechanisms, as individual units which are removably sup- 95 ported in the column of the machine, thus providing for the convenient repair or replacement of the parts.

Other features of the invention will be- 95 come apparent from a consideration of the accompanying specification taken in connec- 98 tion with the drawings in which:—

Fig. 1 is a front elevation of the machine with parts of the casing broken away;

Fig. 2 is a perspective view of the frame 100

carrying the buttoning mechanism removed from the casing and with the raceway and button-feeding finger detached; and

5 Fig. 3 is a plan view of the operating parts at the top of the machine, the casing having been removed to expose the parts, showing a shoe in position in the raceway.

When a finished shoe has reached the 10 packing room of the factory, it is usually desired to button all the buttons of the upper before inserting the shoe in its carton in order that it may maintain its shape and present its best appearance when removed from the carton for display to the customer.

15 To this end, in my improved machine the buttons of the button fly are inserted in the slot of a raceway disposed approximately in a vertical plane, beginning with the top button if it is a left-hand shoe or with

20 the bottom button if it is a right-hand shoe. Fly-feeding fingers are then engaged with the buttonhole which corresponds to the button which was first inserted in the raceway, and when the machine is set in motion

25 the first button and the corresponding buttonhole will be fed by the machine into position at the end of the raceway where buttoning instrumentalities will operate to spread open the buttonhole across the slot

30 at the end of the raceway and to push the corresponding button through the opened buttonhole. The feeding fingers will then recede to engage the next button and the corresponding buttonhole and the buttoning

35 instrumentalities will release the parts upon which they have just operated and the cycle of the machine will be repeated until all the buttons of the shoe have been inserted in their buttonholes.

40 For the purpose of use in the packing room of the factory, the machine is preferably arranged so that the operator may present work thereto while standing upright. To this end a casing 10 is provided, which

45 is in the form of an upright rectangular box of such a height that the operating instrumentalities which are disposed near the upper end of the machine will come at a height convenient for the presentation of

50 work thereto by an operator standing on the floor. The working parts of the machine, comprising driving mechanism, controlling mechanism and operating mechanism, are enclosed within this casing and

55 are mounted upon three subframes 12, 14 and 16, each of which is removably supported in the casing 10 by means of cross- rods 18 passing through suitable bosses 20 in the casing. Various covers, one of which

60 is indicated at 22, provide access to the interior of the casing for the removal or repair of the various parts. A driving motor 24 is mounted on the lowermost subframe 16 and has a gear-driven stub shaft

65 25 which is belt connected to a controlling

mechanism comprising a shaft 26 upon which there is mounted an automatic counting and stop mechanism like that described in my application Serial No. 704,519, filed April 5, 1924, the setting of which is determined by a manually settable control lever 28. From this shaft 26 power is transmitted to a cam shaft 30 by means of gears 32 and thence to the operating mechanism of the buttoning machine. A hand wheel 33 is 75 provided on said shaft 30 for the operator in case it is desired to turn the machine over manually. The operating instrumentalities of the machine are like those described in United States Letters Patent No. 80 1,497,007, granted June 10, 1924 upon my application, to which reference may be had for a fuller description of parts not fully described herein.

The button guide or raceway plate 40 85 is removably attached to the upper part of the casing 10 in an upright plane substantially flush with the front of the casing and is provided with a slot 42, the sides of which are connected at their outer or receiving end 90 by a loop 44 somewhat offset from the plane of the rest of the raceway, as shown in Fig. 3, in order to facilitate the insertion of buttons in the slot of the raceway. The shanks of buttons inserted in the raceway 95 will be substantially horizontal and the button heads will be behind the raceway plate. As has already been mentioned, the slot of the raceway is disposed in a plane nearly enough a vertical plane so that, as the raceway supports the shoe, the weight of the finished shoe will not have any tendency to push the top of the toe of the shoe into contact with the raceway or the associated 100 operating instrumentalities. The curved slot 105 of the raceway also extends upwardly in a direction relative to the base of the machine exactly similar to the direction which the line of buttons on the shoe has relative to the bottom of the shoe as said shoe is in 110 position on the wearer's foot so that the top of the shoe, including the button fly and the buttonhole fly, occupies substantially its normal relation to the bottom of the shoe during the time that it is being passed 115 through the machine. It will be noted that a lip 45 provided adjacent to the delivery end of the raceway turns aside the free edge of the button fly to prevent any interference between said button fly and the buttoning 120 instrumentalities. An aperture 46 is provided in the raceway plate to provide for the pivoting of a notched button-feeding finger 50 (Fig. 1) between the arms 51 of a slide 52 mounted in ways in the subframe 125 12 for horizontal reciprocation to move the notch of the button-feeding finger along the raceway and feed the buttons toward the delivery end thereof. A spring 54 is provided between an extension of the finger 50 130

and one of the arms 51 on the slide 52 tending to push the notched end of the finger toward the slot of the raceway, and said notched end engages a recess (not shown) 5 running along the upper edge of the raceway slot 42 so that it follows the path of the raceway slot. Actuation of the slide 52 to secure feeding of the buttons is effected by means of a lever 56 which, like 10 all of the other buttoning instrumentalities except the button-feeding finger 50, is disposed behind and substantially concealed by the raceway plate and is pivoted to the subframe 12 and forked at its upper end (Fig. 15) 3) to receive a block 58 pivotally attached to the rear side of the slide 52. A link 59, connecting the lever 56 with another moving part of the machine, as will later appear, provides motion for the button-feeding parts 20 by means of which the buttons are fed along one after another and brought to the delivery end of the raceway.

Feeding of the buttonholes of the button-hole fly, to bring them one after another 25 into position for the insertion therein of a button as it is delivered to the end of the raceway, is accomplished by means of fly-feeding fingers 60 and 62 (Fig. 2) which are attached to a block 64 (Fig. 3) carried 30 at the upper end of an arm 66 which is pivotally attached at 68 (Fig. 1) to the subframe 12. This arm is oscillated by means of a cam-operated lever 70, which is connected to the arm 66 by a link 72 in a manner to be later described, and it is the arm 66 to which the link 59 is connected in order 35 to provide motion for the lever 56, which actuates the button-feeding mechanism. The fly feeders and button feeder therefore move 40 in unison to bring the buttons and the buttonholes of the buttonhole fly into the desired position at the end of the raceway. A cam path 74 in a cam 76 upon the cam shaft 30 actuates the lever 70.

In order to secure the proper positioning 45 of the buttonholes of the buttonhole fly at the delivery end of the raceway, the block 64, upon which the fly-feeding fingers 60 and 62 are mounted, is carried by a spindle 50 80 which turns in bearings 82 and 84 formed integral with the arm 66. The finger 62 is rigidly secured to the block 64, and adjustably mounted upon the upper surface of said finger is a narrow plate 86, at the 55 lower end of which is an edge gage 88 adapted to ride against the edge of the buttonhole fly as the fingers are being moved rearwardly along said fly to enter the next succeeding buttonhole, as will be later described. The other fly-feeding finger 60, which is pivotally mounted on the block 64 and has a hooked outer end, is provided with a depending thumb 90 to which is connected a tension spring 92 normally holding 60 the pivoted finger 60 in contact with the rigid finger 62. The turning movement of the spindle 80 in the bearings 82 and 84 is controlled by a torsion spring 94 surrounding said spindle and adjustably tensioned by means of a knurled nut 96 (Fig. 1). An 70 arm 100, rigidly secured to the block 64 at the upper end of the spindle, is provided with a roll which is held in contact with a cam plate 98 by the torsion spring 94. The cam plate 98 is preferably adjustably secured to a part of the subframe 12. A guide member 99 prevents twisting or bending of the arm 66.

The fly-feeding fingers are first separated by the operator and inserted in the first 80 buttonhole. To this end, a manually operable lever 101 (Fig. 1) having a finger piece 103 and held in one position by a spring 105 is pivoted upon the subframe of the machine just back of the raceway plate 85 40. The left end of this lever 101 is positioned to coact with the lower side of the thumb 90 to lift the finger 60 when the arm 66 brings said fingers to rest position away from the button-inserting position. 90 Thereafter these fingers act to carry a buttonhole to the head of the raceway and deliver it to other mechanism to be described and then, while the buttonhole fly is gripped by said mechanism, to travel back along the 95 buttonhole fly with the rigid finger 62 upon one side of the buttonhole fly and the pivoted finger 60 dragging against the outer side of the buttonhole fly until said pivoted finger enters the next succeeding buttonhole. It 100 should be noted that, in view of the fact that the cam track 74 provides a throw of positive extent for the lever 70, no provision has been made in the apparatus so far described for the condition which arises when 105 the spacing between various buttonholes is uneven or deliberately varied. To meet this condition and to avoid tearing the button-hole fly when the fly-feeding fingers are moved along the fly and enter the next succeeding buttonhole, an impositive connection 110 is provided between the link 72 and the arm 66. In brief, this connection comprises a bell-crank lever pivotally connected at one end to the link 72 and at the other end to the arm 66 and having at the elbow of the bell-crank a roll 102 which is guided in a slot of an arm 104 pivotally connected to the subframe 12 and controlled by a spring 106 extending to another portion of the subframe, which tends to hold the end of said slotted arm normally in contact with a suitable stop upon the frame (see Fig. 1). When the arm 66 is being moved forward 115 to deliver a buttonhole to the end of the raceway, the arm 104 comes in contact with the stop on the frame and transmits the movement of the lever 70 positively to the arm 66. On the other hand, when the arm 66 is being moved rearwardly to cause the 120 125 130

fly-feeding fingers to engage the next succeeding buttonhole, if said fingers enter a buttonhole before the lever 70 has reached the limit of its movement, then the spring 106 will allow the slotted arm 104 to turn and prevent any damage to the buttonhole fly. For a more complete description of this arrangement, together with its advantages in ensuring a feed of the buttonhole fly responsive to the spacing between the buttonholes, and other advantages, reference may be had to the above-named Letters Patent No. 1,497,907.

It will be noted from an inspection of Fig. 3 that the fly is guided by the edge of the raceway 40 in a plane substantially parallel to the axis of the buttons in the raceway and that the action of the cam plate 98 is to rotate the spindle 80 carrying the fly-feeding fingers in such a direction that the buttonhole fly is pulled inwardly toward the machine as it approaches the delivery end of the raceway.

When a button and the corresponding buttonhole of the buttonhole fly have been delivered to the end of the raceway, they are taken in charge by the buttoning instrumentalities, which are arranged firmly to grasp the button and the buttonhole fly, to spread open the buttonhole across the delivery end of the raceway, and to push the button into the opened buttonhole. One of the elements of this arrangement consists of a raceway closer 110 pivotally mounted upon an arbor 112 carried in the subframe 12 and provided at its end with a notched foot 114 adapted to engage a corresponding projection upon the end of the raceway and when thus positioned to close the slot of the raceway. A suitable spring 116 (Fig. 1) tends to keep the raceway closer in this position but allows it to be pushed aside. A bell-crank lever 120, which is also pivotally mounted upon the arbor 112, is actuated through one arm 122 by a link 124 from a lever 126 carrying a roll traveling in a slot 128 of the cam 76. The other arm 130 of the lever carries at its outer end fly-gripping fingers 132 and 134, which are arranged to engage the opposite sides of a buttonhole to hold it firmly in position and to open it across the end of the raceway. The finger 134 is rigid with the arm 130 but the finger 132 is pivotally mounted on said arm and held by a spring 136 (Figs. 2 and 3) in a position determined by coacting abutments on said finger and arm. The arrangement is such that the hook-shaped finger 132 will contact with the buttonhole fly adjacent to the right-hand edge of the buttonhole and hold it against the lip 45 on the end of the raceway resiliently, under the tension of the spring 136. Under the continued movement of the arm 130, the other finger 134, gripping the buttonhole fly at the other side of the but-

tonhole against the raceway closer 110 moves the left-hand edge of the buttonhole across the slot at the end of the button raceway and opens the buttonhole by moving the edges relatively to one another and transversely of the plane of the buttonhole fly. This prevents any serious strain upon the buttonhole fly and allows the finger 134 to prevent the edge of the buttonhole from being torn or turned up in the way of the button as the latter is pushed out of the raceway. At the same time, the end of finger 134, acting through the buttonhole fly, pushes aside the button-feeding finger 50.

To push the button out of the raceway into the buttonhole, I have provided a button pusher 140 on the end of a lever pivotally mounted at 142 in the subframe 12 and actuated, by a link connection, from a lever 144, which is moved in a prescribed course by a roll thereon engaging with a track 146 in the cam 76. This lever is also provided with an outwardly extending pin 148 adapted to engage a slide 150 for the actuation of a suitable counter 152 to record the number of buttons which have been inserted in the buttonholes. Carried on this same lever which carries the button pusher 140 is a wiper 154 which is adapted to engage the thumb 90 upon the fly-feeding finger 60 in order laterally to displace said finger to remove it from the buttonhole when the button pusher moves the button toward the buttonhole in order to prevent interference between the two.

A finger for clamping the button against the raceway to prevent the button pusher from tipping the button as it is moving it out of the raceway is provided upon the outer end of an arm 160 pivotally mounted in the subframe 12 and pressed forwardly by a spring (not shown) to cause it to engage the crown of the button and hold its base against the rear side of the button raceway. A suitable cam surface 162 is provided upon the forward side of the button clamping finger in position to coact with a cam surface on the button pusher 140 so that, as the button pusher is retracted, it lifts the clamp away from the buttons in the raceway and, as it starts forward, it allows the clamp to grasp the button at the end of the raceway just prior to its removal therefrom by the button pusher.

In operating the machine, all the buttons on the button fly will be inserted in the slot of the raceway by the operator, beginning with the top button if it is a left-hand shoe and beginning with the throat button if it is a right-hand shoe. The buttonhole corresponding to the button which was first inserted in the raceway will then be placed between the fly-feeding fingers 60 and 62, which are separated by depression of the manually operated lever 101 to facilitate

this operation, and the first button in the raceway slot will be dragged into the notch of the button-feeding finger 50. As power is supplied to the machine, after the depression of a treadle, shown in Fig. 1, the feeding fingers 50, 60 and 62 will start forward and carry a button and the corresponding buttonhole into position adjacent to the delivery end of the raceway. The raceway closer 110 will prevent the accidental removal of the first button from the raceway at this time, and as the buttonhole fly approaches a position at the delivery end of the raceway, it will be carried inwardly away from the operator by the coaction of the cam plate 98 and the arm 100 on the spindle carrying the fly-feeding fingers. This will bring it into such a position that the full width of the buttonhole will be approximately opposite to the maximum width of the button. As the operation of the machine continues, the gripping fingers 132 and 134 will successively contact with the buttonhole fly upon opposite sides of the buttonhole and clamp the right-hand side of the buttonhole against the lip 45 upon the raceway and thrust aside the left-hand side of the buttonhole, pushing it downwardly against the foot 114 of the raceway closer and displacing the latter and the button-feeding finger 50, as well, from the shank of the button. During this movement of the fly-gripping fingers 132 and 134, the button pusher 140 will have started forward and almost immediately will have allowed the button clamping finger 160 resiliently to engage the crown of the button and hold it in position at the end of the raceway. As the movement of the pusher 140 continues, it will engage the head of the button laterally and push it out from beneath the clamp 160 into the buttonhole which has been spread open across the delivery end of the raceway. Just after the holding clamp engages a button, the wiper 154 will have engaged the thumb 90 formed integrally with the fly-feeding finger 60 positively to remove said finger from the buttonhole just prior to the time when the button has passed into said buttonhole. The fly-feeding fingers will then start to move rearwardly (that is to say, to the right along the raceway) while the buttonhole is still clamped by the gripping fingers 132 and 134. As they are dragged along the buttonhole fly, the fingers 60 will engage the next succeeding buttonhole but will not tear the buttonhole fly because of the impositive connection which has been described. The button pusher 140 will act first upon the side of the head of the button and continue so to act until the button is free from the clamping finger, but as the button enters the buttonhole, it will be turned about its point of attachment with the button piece and the point of contact of the end of the pusher and the button will move around to the under surface of the button head, whereupon the button pusher will slide over the button and pass still further into the buttonhole, thus ensuring the complete insertion of the button. As the fly-feeding fingers are moved rearwardly, the button-feeding finger 50 will also be pulled back until the notch therein has engaged the shank of the next succeeding button. The button pusher 140 and the wiper 154 will then be returned to their original positions, lifting the button-clamping finger 160, and the fly-gripping fingers 132 and 134 will also be lifted to release the buttonhole fly, thus allowing the raceway closer 110 to return to its original position across the end of the slot of the raceway. The machine will then be ready to begin the operation of buttoning the second button.

Having described the invention, what I claim as new and desire to secure by Letters Patent of the United States is:

1. In a buttoning machine for use on finished shoes, a button raceway provided with a slot for the reception of the shanks of the buttons on a shoe, button-feeding and buttonhole-fly-feeding members arranged to carry the buttons one at a time along the raceway to the delivery end thereof and correspondingly to feed the buttonholes of the buttonhole fly into position for the insertion of the buttons, and buttoning instrumentalities for opening a buttonhole across the delivery end of the raceway, removing a button from the raceway, and inserting it in the buttonhole, said button raceway being disposed in an upright plane and so arranged that the weight of the finished shoe will normally hold the top of the toe of the shoe away from the raceway and the operating instrumentalities.
2. In a machine for buttoning finished shoes, a casing provided upon its front face with a plate slotted to provide a raceway for the reception of the shanks of the buttons upon a shoe and fastened with the slot in upright position and the plate substantially flush with the front of the casing, and mechanism for feeding the buttons along the raceway and presenting the buttonholes for the operation of buttoning instrumentalities to cause the insertion one at a time of the buttons in the buttonholes, the greater part of said mechanism being arranged within the casing upon the further side of the raceway plate, with the result that the finished shoe is separated from the operating instrumentalities of the machine by the plate itself.
3. In a machine for buttoning a plurality of buttons of a finished shoe seriatim, mechanism for presenting the buttons one at a time, mechanism for presenting the corresponding buttonholes, members for spreading open said buttonholes, and a

pusher for inserting a button into an opened buttonhole, together with a slotted raceway for supporting and guiding the buttons of the button piece, said raceway being constructed and arranged so that the shanks of the buttons are positioned substantially horizontally with the heads of the buttons away from the operator with the result that the finished shoe, as it is supported largely by the buttons in said button raceway, hangs freely in a plane substantially parallel to the plane of said button raceway and substantially without interference therewith or with the operating parts of the machine.

15 4. In a machine for buttoning finished shoes, a slotted plate forming a raceway secured in upright position on the front face of the machine to receive the shanks of the buttons upon a shoe with the button heads 20 behind the plate, a button feeder for passing the buttons along the raceway, a fly feeder for delivering the buttonhole fly to position a buttonhole at the end of the raceway, and buttoning instrumentalities for inserting the 25 buttons in the buttonholes, said button feeding device being disposed upon the front side of the raceway plate and the other mechanism being disposed upon the rear side of the raceway plate.

30 5. In a machine for buttoning finished shoes, a frame, a slotted substantially plane raceway plate secured to said frame with its slot disposed in substantially a vertical plane, buttoning instrumentalities located 35 behind the plane of the raceway plate and substantially concealed thereby, and a cam shaft for operating said buttoning instrumentalities disposed substantially vertically below and on the same side of the plane of 40 the raceway plate as said buttoning instrumentalities.

6. A machine for buttoning bottomed shoes by inserting by inserting the buttons one at a time in the corresponding buttonholes of the buttonhole fly comprising a slotted raceway plate for the reception of the buttons on the button fly, and buttoning instrumentalities associated with said raceway, said raceway and buttoning instrumentalities being constructed and arranged 50 to support the top of the shoe, including the

button fly and the buttonhole fly, in substantially its normal relation to the bottom of the shoe during the time that it is being passed through the machine and through 55 the top to support the bottom of the shoe.

7. A machine for buttoning shoes to which the bottom has been applied comprising a substantially plane raceway plate having a curved slot for the reception of the buttons 60 on the button fly, said raceway being so supported upon the machine that the slot extends upwardly in a direction relative to the base of the machine exactly similar to the direction which the line of buttons on the 65 shoe has relative to the bottom of the shoe as said shoe is in position upon the wearer's foot.

8. In a buttoning machine relatively separable fly-feeding fingers carried upon a 70 swinging arm to feed the buttonholes of a buttonhole fly one at a time into position for the insertion therein of the corresponding buttons, and a manually operable lever pivoted upon a fixed fulcrum in the machine 75 arranged for coaction with said fingers to separate the fingers when the carrying arm is in a position removed from the button-inserting position.

9. In a machine of the character described, a hollow supporting column, buttoning mechanism within and removably supported in said column at its upper end and arranged to insert a plurality of buttons seriatim, controlling mechanism comprising a device for starting the operation of the machine under the control of the operator and an automatic device for stopping the operation of the machine at the conclusion of a predetermined number of buttoning operations, said mechanism being removably mounted in an intermediate part 80 of the column, detachable driving connections between said controlling mechanism and the buttoning mechanism, a driving 85 motor removably mounted within said column at its base, and detachable driving connections between said motor and said controlling mechanism.

In testimony whereof I have signed my 100 name to this specification.

LEWIS J. BAZZONI.
